US0D1051123S

(12) **United States Design Patent** (10) **Patent No.:** **US D1,051,123 S**
(45) **Date of Patent:** **** Nov. 12, 2024**

(54) **TABLET COMPUTER**

(71) Applicant: **Shenzhen Efercro Electronic Technology Co., Ltd**, Guangdong (CN)

(72) Inventor: **Chao Peng**, Guangdong (CN)

(73) Assignee: **Shenzhen Efercro Electronic Technology Co., Ltd**, Shenzhen (CN)

(**) Term: **15 Years**

(21) Appl. No.: **29/880,744**

(22) Filed: **Jul. 27, 2023**

(51) LOC (14) Cl. **14-02**

(52) U.S. Cl.

USPC **D14/341**

(58) **Field of Classification Search**

(57) **CLAIM**

The ornamental design for a tablet computer, as shown and described.

DESCRIPTION

FIG. 1 is a front and top perspective view of a tablet computer, showing my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the figures depict portions of the tablet computer that form no part of the claimed design.

1 Claim, 8 Drawing Sheets
